CLAIM

The ornamental design for a container for disc-shaped recording medium, as shown and described.

DESCRIPTION

FIG. 1 is a front elevational view of a container for disc-shaped recording medium showing our new design;

FIG. 2 is a rear elevational view of the container;

FIG. 3 is a top plan view of the container;

FIG. 4 is a bottom plan view of the container;

FIG. 5 is a right side elevational view of the container;

FIG. 6 is a left side elevational view of the container;

FIG. 7 is a front elevational view of the container in its open state;

FIG. 8 is a cross-sectional view taken on line VIII—VIII in FIG. 7;

FIG. 9 is a cross-sectional view taken on line IX—IX in FIG. 7;

FIG. 10 is a bottom and right perspective view of the container; and,

FIG. 11 is a bottom and right perspective view of the container in use. The broken lines showing a compact disc, in FIG. 11, illustrate a feature that forms no part of the claimed design.
